UNITED STATES PATENT OFFICE

2,385,726

NECKTIE

Giuseppe F. Pinsuti, New York, N. Y.

Application December 4, 1943, Serial No. 512,869

2 Claims.

(Cl. 2—146)

This invention related to neckties of the kind known as four-in-hand which is a long necktie lined to give it body, worn tied in a knot that leaves end portions hanging vertically from the knot.

An object of the invention is to so incorporate the lengthwise seam of a four-in-hand necktie as to eliminate the resistance at the center across the knot portion when the necktie is tied, and to dispose it that the knot may be easily formed without the material spreading and thereby making the knot smooth and shapely and the hanging ends dimpled at the center so that it may be worn tied, with the desired elegant effect.

A further object of the invention is to form the lengthwise seam of the components of the necktie at one side of its longitudinal axis or center line, to the end that less material than usual is required to make a necktie of the regular size.

A further object of the invention is to provide a lining with less resistance in the center in the knot portion of the necktie and more on the side.

A further object of the invention is to simplify the manufacture of a four-in-hand necktie by reason of the materials being stitched together along the lateral edges thereof, and in carrying out this operation said materials may be easily and conveniently laid together to receive the stitching for the formation of the off-center seam with a saving of time and labor.

The nature of the invention and its distinguishing features and advantages will appear when the following specification is read in connection with the accompanying drawing, in which:

Fig. 1 is a view of a finished necktie embodying the features of the invention, the same being laid at full length and viewed from the inside.

Fig. 2 is a view similar to Fig. 1 showing the necktie before it is turned inside out.

Fig. 3 is an enlarged transverse sectional view taken on the line 3—3 of Fig. 2.

Fig. 4 is an enlarged transverse sectional view taken on the line 4—4 of Fig. 1.

Fig. 5 is a view showing how the parts of the necktie are cut to selected patterns from a piece of goods forty-one inches in width.

Fig. 6 is a view showing the cut parts of Fig. 5 laid together to be joined to form the bias seam and as they appear before being folded longitudinally.

Fig. 7 is an enlarged transverse sectional view showing a modification of the seam.

As stated, the present invention is embodied in a necktie of the style known as a four-in-hand. Different textile materials or fabrics are used and these materials usually are in a width of twenty-four inches from which the parts of the necktie are cut according to selected patterns.

The cut parts are sewn together to form the usual tubular structure which is turned inside out so that the finished surface of the fabric will be on the outside. The necktie is composed of two parts sewn together to provide the usual neckband portion and front and rear tabs or ends. The article is lined to give it body according to the kind of fabric used, whether heavy or light in weight. Where heavy fabric is used, a strip of lining of single ply is used; whereas, in the case of the use of fabric light in weight, a lining of two thicknesses or plies is used. Approximately one-third of a yard of fabric per dozen of neckties is saved in using twenty-four inch width fabric, and approximately one-half of a yard in using forty-one inch width fabric.

The two parts 10 and 11 are cut according to selected patterns from a piece of desired textile material or fabric. The part 10 embodies the front end and part of the neckband and the part 11 embodies the rear end and the remainder of the neckband. These cuts include cuts 12 and 13 of the parts 10 and 11 respectively across the grain of the material. Also, the parts are cut with a flare and the usual points as shown in Fig. 5. The parts 10 and 11 are sewn together flatwise along the diagonal edges 12 and 13 so that the parts 10 and 11 are seamed as at 14 in continuation of each other, end to end in a single structure, as shown in Fig. 6. This structure is folded upon itself longitudinally to bring the lateral or longitudinal edges 16 thereof at one side of the longitudinal axis of the tubular structure now formed by the folding operation, as shown in Fig. 3.

In order to give body to the necktie, use is made of a lining 17 of suitable textile material. When the parts 10 and 11 are made of relatively lightweight fabric, a piece of a material to serve for the lining is folded upon itself to provide two thicknesses or plies, as shown in the present instance. When relatively heavy-weight fabric is used, the lining is of a single ply or thickness.

The lining 17 is laid on the tubular structure aforesaid with its edge portions at one side of the lining paralleling and approximately coincidental with the lateral edges 16. Stitching 18 passes through one edge of the lining and said edge portions 16 to secure the lining to the ma-

terial of the necktie at the seam 19 formed between said edge portion 16. This seam extends lengthwise of the necktie on the inside and at one side of the center line or longitudinal axis thereof.

The lining 17 has a series of cuts or slits 20 which will occur in the knot portion parallel to the weave of the material so as to reduce the center resistance of the lining.

The sewn structure shown in Fig. 2 is turned inside out to produce the finished article, in which the lengthwise seam is lapped on itself, as shown in Fig. 4. In Fig. 7, the necktie has a single ply lining 17 stitched along one longitudinal edge to the longitudinal edges of a folded piece of material. The sewn structure is turned inside out and the lengthwise seam 119 is overlapped toward the center in accordance with the invention. The article will be a four-in-hand necktie having flaring ends or tabs and may be worn tied in a knot that leaves the ends or tabs hanging vertically with the large end in front of the small end, as will be understood.

By virtue of the construction of the necktie as set forth hereinabove, it may be worn tied with the desired effect and appearance by elimi-

nating spreading and twisting of the materials and eliminating the resistance from the center in the knot portion and placing it on the side, and from the point of view of costs of production saves materials and labor.

I claim:

1. A necktie consisting of textile material, a seam joining the longitudinal edges of the material to provide a tubular structure shaped and adapted to be turned inside out and locate said seam between the center and one side edge of the structure, and a textile lining within said structure secured along one of its longitudinal edges to said seam and the lining being doubled upon itself along the other longitudinal edge portion and loose within said structure to provide resistance at the side opposite the seam.

2. A necktie consisting of a tubular fabric structure having one longitudinal edge portion finished with a seam overlapped, and a lining doubled upon itself within said structure with the fold line at the side of the structure opposite the aforesaid seam to render the center portion of the structure less resistant than the sides.

GIUSEPPE F. PINSUTI.
